CLAIM

The ornamental design for a hair dryer as shown and described.

DESCRIPTION

FIG. 1 is a front, right and top perspective view of a hair dryer, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged top plan view of the hair dryer;

FIG. 8 is an enlarged bottom plan view of the hair dryer.

FIG. 9 is an enlarged view of a portion of the hair dryer shown within the area designated as 9 in FIG. 1; and,

FIG. 10 is an enlarged view of a portion of the hair dryer shown within the area designated as 10 in FIG. 2.

The dashed broken lines depict portions of the hair dryer that form no part of the claimed design. The dot-dash broken lines in FIGS. 1, 2, 9, and 10 depict the boundaries of the enlargements and form no part of the claimed design.

1 Claim, 10 Drawing Sheets
